UNITED STATES PATENT OFFICE.

HARRY H. SCHROYER, OF CHICAGO, ILLINOIS, ASSIGNOR TO DUNBAR MANUFACTURING COMPANY, OF CHICAGO, ILLINOIS, A CORPORATION OF ILLINOIS.

METAL-ROOF STRUCTURE AND SEAL FOR CAR-DIAPHRAGMS.

1,256,059.

Specification of Letters Patent. Patented Feb. 12, 1918.

Continuation of application Serial No. 86,618, filed March 26, 1915. Patent No. 1,256,055, dated February 12, 1918. This application filed February 1, 1917. Serial No. 145,914.

To all whom it may concern:

Be it known that I, HARRY H. SCHROYER, a citizen of the United States, and a resident of the city of Chicago, in the county of Cook and State of Illinois, have invented certain new and useful Improvements in Metal-Roof Structures and Seals for Car-Diaphragms; and I do hereby declare that the following is a full, clear, and exact description of the same, reference being had to the accompanying drawings, and to the numerals of reference marked thereon, which form a part of this specification.

This application constitutes a continuation of my co-pending application for "Metal car diaphragms," filed March 26, 1915, Serial No. 86,618.

This invention relates to an improved roof structure and seal therefor for use with metal type car diaphragms whereby adjusting and flexing movements of the diaphragm with respect to the car are permitted to take place, yet with the roof member affording a water tight shelter over the side walls of the diaphragm and with sealing means mounted on the car co-acting with the roof member to provide sealing connection between the same and the car.

It is also an object of this invention to construct a car diaphragm provided with a roof structure of improved design, and equipped with sealing means to afford an efficient weather seal at the connection between the roof structure and the car itself.

It is also an object of this invention to construct an improved telescoping type of roof structure for metal car diaphragms having an adjustable connection with the side walls of the diaphragm to permit warping or flexing movements of the diaphragm with respect to the car and between the parts of the diaphragm, and with sealing means associated with said roof structure to afford an efficient seal at all points of connection thereof with the side walls of the diaphragm and the car itself.

It is furthermore an important object of this invention to construct a car diaphragm metal roof capable of longitudinal extension and contraction with respect to the car as well as lateral adjusting movements, and yet in all variations of movement and positions of adjustment effectually sealed with

the side walls of the diaphragm and with the car body itself.

It is finally an object of this invention to construct an improved type of roof structure for metal car diaphragms simple in operation and construction and operating efficiently to afford a weather proof passage through the vestibule diaphragm of a car.

The invention (in a preferred form) is illustrated in the drawings and hereinafter more fully described.

In the drawings:

Figure 1 is a fragmentary vertical section taken through the upper end of a car vestibule diaphragm, embodying the principles of my invention.

Fig. 2 is a fragmentary top plan view with parts broken away and shown in section of a roof structure embodying the principles of my invention.

Fig. 3 is a detail section taken on line 3-3 of Fig. 1, with parts omitted.

Fig. 4 is a fragmentary detail section taken on line 4-4 of Fig. 1, with parts omitted.

Fig. 5 is a detail section taken on line 5-5 of Fig. 1.

Fig. 6 is a fragmentary detail section taken on line 6-6 of Fig. 2.

As shown in the drawings:

The reference numeral 1, indicates as a whole a car body on which is secured by means of rivets, bracing or other suitable means an angle end beam or plate 2, which arches over the vestibule opening at the end of the car. What may be termed the stationary member of the car vestibule diaphragm is adjustably connected upon beam uprights 3, forming a part of the end structure of the car and said stationary member comprises side walls 4 and 5 respectively of which the upper margin of each of the walls 4, is flanged inwardly as denoted by the reference numeral 6, and provided with a strip of sealing material on its upper surface. The rear marginal portion of each of the inner side wall plates 4, is flanged outwardly to receive the rear flanged margin of the wall plates 5, brazed or otherwise rigidly secured thereto, and is bent into parallel relation with said plates 4 and 5, as denoted by the reference numeral 7, and at its extreme margin beaded over as denoted by the ref-

rence numeral 8. Secured upon the rear surface of the I-beam upright 3, is a resilient retaining plate 9, one margin of which is beaded over to interfit with the 5 beaded portion 8, of the side wall member and a wear plate is mounted beneath the said retaining plate 9, against which the beaded portion 8, is confined. This connection of said side wall to the I-beam frame 10 member 3, affords an adjustable connection for the stationary section of the diaphragm.

Inserted between the outer flanged margins of the respective side wall plates 4 and 5, are thin plates 11 and 12, on which sealing strips 13, are secured, as clearly shown in detail in Fig. 5. Rigidly mounted with the ends of the car is a vertical plate 14, and secured along the upper portion thereof and extending horizontally outwardly and 20 gabled or apex-shaped is a stationary roof section or top member 14. The lower margin of said vertical plate 14, is flanged inwardly and rigidly secured thereto is a horizontal stationary ceiling plate 16. Also secured upon said vertical frame plate 14, and projecting outwardly horizontally therefrom is an apex compartment member 17, which together with the gabled roof or top member 15, affords an angled compartment to 25 receive the apex or gabled roof member of the movable section of the diaphragm therein hereinafter described.

The movable section of the diaphragm is attached upon a face plate 18, and consists 30 of side walls 19, the rear margins of which telescope between the sealing members 13, into the narrow compartment between the side walls 4 and 5, of the stationary section, and the gabled or apex-shaped roof member 40 20, which is shown in plan view in Fig. 2, is of trapezoidal shape and adjustably connected to said side walls 19. The means of attachment of said side walls 19, to the face plate 18, consists of a wear plate 21, secured 45 upon the face plate with a resilient retaining plate 22, secured thereover, and bent outwardly and beaded inwardly to receive the beaded margin 24, of the side wall engaged adjustably therein. The roof member 20, is 50 flanged outwardly at its forward margin as clearly shown in Fig. 1, and rigidly secured to the upper portion on the rear surface of the face plate 18. The adjustable connection between the roof member 20, and the 55 side walls 19, is shown in detail in Figs. 3 and 4, and for this purpose, the side margins of the roof member 20, are bent inwardly as denoted by the reference numeral 25, and the top margin of the side walls 19, 60 are also flanged inwardly therebeneath with the extreme marginal portion bent in an acute angle to afford a limiting stop for the movement of the inwardly flanged portion 25, of the roof member 20. A strip of sealing material 28, is interposed between said

respective inwardly flanged portions 25 and 25, to afford a seal therefor.

Pivottally secured to the rear surface of the face plate 18, beneath the gabled roof member 20, is a rearwardly horizontally extending rod 29, which extends through the apex compartment 17, and slidably through the rear frame plate 14, and has coiled therearound a compression spring 30, so that said spring serves to resist inward movement 75 of the face plate and associated elements of the diaphragm section therewith.

A sealing device is provided mounted on the end of the car for sealing along the exterior surface of the movable roof member 80 20, to effectually seal the same at its point of entrance into the telescoping members of the diaphragm in all movements and in all positions of adjustment thereof. Pivottally mounted in inclined position on the front of 85 the car end above the top wall member 11, are plates 31, angled with respect to one another and parallel to the gabled roof member 20. The lower ends of said plates are provided with a sealing strip 32, and springs 90 33, are associated with the hinged connection for said plates 31, to bear upon said plates and impel the sealing strip downwardly upon the respective inclined surfaces of said roof member 20, to seal therealong. 95

The operation is as follows:

The outer side wall sections 19, of the diaphragm are adapted to move inwardly telescoping with the respective side walls 4 and 5, which are adjustably mounted on the 100 ends of the car so as to be capable of slight lateral movement. The roof member 20, moves beneath the stationary gabled roof member 15, within the end of the car, the spring impelled sealing means 32, sliding 105 over the surface thereof as said roof member moves inwardly therebeneath. Said roof member 20, is not only of gabled or apex shape, but converges rearwardly from the face plate 18, rearwardly to its rear margin 110 as clearly shown in the plan view in Fig. 2, so that said roof member is capable of a transverse swinging movement rigid with the face plate 18, when such movements are imposed upon the face plate. Relative movements between the side walls 19, and said roof member 20, is permitted owing to the fact that a sliding sealing connection is provided therebetween, the top margins of said 115 side walls being flanged inwardly and the side margins of said roof member also being flanged inwardly and bearing downwardly thereon with the strip of sealing material therebetween.

I am aware that various details of construction may be varied through a wide range without departing from the principles of this invention, and I therefore do not purpose limiting the patent granted otherwise than necessitated by the prior art. 125

I claim as my invention:

1. In a device of the class described the combination with a metal diaphragm, of a roof structure capable of relative movement
  - 5 as a unit with respect to the side walls of the diaphragm, and a sealing means mounted upon a car upon which the diaphragm is attached adapted to seal on the exterior of said roof member in all positions of movement and adjustment thereof.
  - 10 2. In a device of the class described the combination with a vestibule diaphragm attached on a car, of sealing means adjustably mounted upon a car to seal along the exterior of the diaphragm in all positions of movement and adjustment thereof with respect to the car.
  - 15 3. In a device of the class described the combination with a car and a metal diaphragm adjustably mounted thereon, of sealing means adjustably mounted upon the car and co-acting with said diaphragm to afford a seal between the same and the car in all positions of movement and adjustment of the diaphragm.
  - 20 4. In a device of the class described the combination with side walls of a vestibule diaphragm attached on a car of a roof member adjustably and sealingly associated therewith and sealing means pivotally mounted on the car to afford a sealing connection between said roof member and the car.
  - 25 5. The combination with a telescoping metal vestibule diaphragm mounted on a car, of sealing means adjustably mounted on the car co-acting with one of the telescoping sections of the diaphragm to afford a sealing connection between the same and the car.
  - 30 6. In a device of the class described the combination with a metal vestibule diaphragm mounted on a car, of sealing means
  - 35
  - 40
  - 45
  - 50
  - 55
  - 60
  - 65
  - 70
  - 75
  - 80
  - 85
  - 90
  - 95
- adjustably mounted upon the car adapted to seal along the roof member of said diaphragm in all positions of adjustment thereof.
7. In a device of the class described the combination with a roof member of a vestibule diaphragm adjustably mounted with respect to the side walls of the diaphragm, of sealing means mounted on the car on which the diaphragm is attached adapted to co-act with said roof member to afford a seal between the same and the car.
8. The combination with a car and its vestibule diaphragm, of a roof member forming a part of said diaphragm adjustable with respect thereto, of sealing means adjustably mounted to co-act with said roof member in effecting sealing connection between the roof member and the car.
9. In a telescoping metal car diaphragm construction, a metal roof member adjustably and sealingly associated with the side walls of the diaphragm, and sealing means adjustably mounted on the car to coact with said roof member to effect a seal between the same and the car.
10. In a construction of the class described the combination with the face plate and side walls of a vestibule diaphragm of a roof member rigidly secured to said face plate and movable therewith relative to said side walls and in sealing relation therewith, and sealing means pivotally mounted on the car adapted to co-act with said roof member to seal the same in all positions of adjustment.

In testimony whereof I have hereunto subscribed my name in the presence of two subscribing witnesses.
